DOOR OPERATING AND LOCKING
MECHANISM

Anthony Schneider, Silverton, Ohio

Application November 13, 1936, Serial No. 110,719

7 Claims. (Cl. 189—7)

This invention relates to control means for a door whereby the door may be closed and secured, from a remote location, and thereafter automatically released upon the expiration of a predetermined time interval. The invention is thus applicable for use in connection with banks, jails, etc.

An object of the invention is to provide novel means for actuation, securing, and release of the door, and as will appear, a particular object is to provide for closure of the controlled doorway notwithstanding blocking of the normal closing path of the door.

The exact nature of the invention together with further objects and advantages thereof will be apparent from the following description taken in connection with the accompanying drawings, in which Figs. 1 and 2 are views in elevation from the front and rear respectively, of a swinging or hinged type of door in which the invention is embodied, the door being in closed position and parts in Fig. 2 appearing in section to show details of construction, the latter view showing also the door-actuating mechanism; Fig. 3 is a typical horizontal section of the door as in the plane of line 3—3, Fig. 2; Figs. 4 and 5 are views corresponding with Fig. 3 but showing the door in Fig. 4 in open position and in Fig. 5 with its parts as where the door is blocked as indicated in broken lines; Fig. 6 is a sectional detail as in the plane of line 6—6, Figs. 3 and 4; Fig. 7 is a diagrammatic view showing the door-controlling circuit; and Fig. 8 is a detail in sectional elevation as in the plane of line 8—8, Fig. 2.

With reference now to the drawings, the door shown is mounted for swinging movement between open and closed position to control its doorway, and comprises two parts 1a and 1b, of which the part 1a is hinged as at 2 at a side of the doorway. This part 1a may be of grille type and is so proportioned with respect to the doorway that in closed position its free edge will provide a clearance from the corresponding side of the doorway and extending to the bottom of the doorway, of substantial width but insufficient to permit passage of a person therethrough. The other door part 1b is mounted for normal movement together with the first door part as a unit, but is capable under emergency conditions, of movement independent of the first door part. The second door part which may be solid, is cooperative with the first door part for complete closure of the doorway when in closed position. As here shown the second door part is hingedly mounted upon the first door part as at 3 so that it may have

independent swinging motion about an axis adjacent the axis 2 as indicated in Fig. 5. To cause the two door parts to normally move together, a breakable connection is provided such as by one or more shear pins 4 replaceably mounted as indicated in Fig. 8.

From the arrangement described it will be apparent that should sufficient force be applied to the door part 1a to close the door, notwithstanding such obstruction to the door part 1b as indicated at A, Fig. 5, the pins 4 will be sheared and the doorway effectively barred.

Power means are provided for so closing the door part 1a, shearing the pins 4 if necessary. For the purpose the door part 1a is provided with one or more projections 5, three being indicated, and for each projection a plunger 6 is mounted in a bracket 7. For each plunger 6 an actuating screw 8 is rotatably mounted in the bracket 7, having threaded relation with the plunger. Co-incident drive of all the screws 8 is provided as by a chain 9 running over sprockets 10, one for each plunger. For drive of the screws, a motor 11 is provided connected by suitable gearing 12 to the lowermost screw 8.

It will be apparent that by the arrangement described and commencing with the door open as in Fig. 4, operation of the motor in the proper direction to extend the plungers 6, will cause the latter to engage their projections 5 upon the door with a camming action and will force the door to the closed position of Fig. 3, breaking the shear pins 4 if the door part 1b be obstructed as in Fig. 5. The door being thus closed, it is so secured by the irreversible nature of the drive provided by the screws 8, but upon reverse operation of the motor 11 to withdraw the plungers 6, the door may be opened in the usual manner.

A control circuit for the motor 11 may be provided as indicated in Fig. 7, wherein power is had from the lines L₁, L₂ and L₃. 13 and 14 are three-pole switches, one for each operating direction of the motor 11. 16 and 17 are switches arranged to be thrown by a projection 18 on one of the plungers 6 as the latter attains the end of a stroke. Thus when the plungers are in the open position as in Fig. 4, the switches 16 and 17 are positioned as in Fig. 7, as the plungers advance in door-closing direction the switch 16 automatically closes, and as the plungers attain the door-closed position of Figs. 3 and 5, the switch 17 which is a double-throw switch, is automatically thrown from the position indicated in Fig. 7 to its opposite position.

19 is a double-throw relay switch controlling

- the main switches 13 and 14 through their actuating coils 13a and 14a respectively. 20 is an automatic timing switch controlled by a cam 21 driven by a timing motor 22. 23 is a bell or other signal device arranged to be energized when the door is closed by the motor 11, and 24 is a switch by which door-closing by the motor 11 is initiated and which may be located remotely from the door.
- 10 Operation for power-closing of the door will be as follows, commencing with the parts positioned as in Figs. 4 and 7.
- Instant depression of the switch 24 completes a circuit including the coil 13a of the switch 13 and starts the motor 11 operating in closing direction to throw the plungers 6. It also throws the switch 19 to its opposite position from that shown, which establishes a maintaining circuit for the coil 13a and starts operation of the signal device 23 through a circuit including the switch 17. As the projection 18 leaves the switch 16, the latter closes. As the plungers complete their door-closing movement, the projection 18 throws the switch 17 which de-energizes the coil 13a opening the switch 13 and stopping the motor 11, and at the same time completes a circuit energizing the timing motor 22 to drive the cam 21 and de-energize the signal device 23. As the switch 13 opens, the switch 19 returns to its initial position. This cam and its drive is so arranged that after a predetermined desired time, say ten minutes, has elapsed, the cam 21 throws the switch 20, opening the circuit of the timing motor 22 and stopping this motor, and completing the circuit for the coil 14a of the reversing switch 14 of the motor 11, this circuit including the switch 16 now closed and the switch 19. The plungers 6 are thus withdrawn by the motor 11, the switch 17 being permitted to return to its original position by the projection 18.
- As the plungers attain their initial open position the switch 16 is opened by the projection 18, de-energizing the coil 14a and stopping the motor 11.
- 45 The cycle of operations is thus completed, the door is free to be reopened, and upon resetting of the timer cam 21 to return the switch 20 to its shown position the parts are preset for initiation of another closing cycle by depression of the switch 24.
- 50 Should the door be already closed when the switch 24 is thrown to initiate the closing cycle, it will be apparent that the power apparatus will merely secure it against opening during the timed period described.
- 55 Obviously when the power closing apparatus is in its usual open position as in Fig. 5, the door may be opened and closed by hand in the usual manner and it may be provided with an ordinary key-operated lock as indicated in Fig. 1 for its normal securement in closed position.
- What I claim is:
1. A door of the class described having two parts arranged for movement between open and closed positions to control a doorway, one of said parts being arranged to provide, in closed position, a clearance from a side of said doorway, of insufficient amount to permit passage of a person therethrough, power means associated with said part for moving it to its closed position, the other door part being arranged to be cooperative with said first part, to complete the closure of said doorway when in closed position, and means interconnecting said door parts to cause their normal operation together as a unit and including

means breakable to permit said power means to close said first part when said second part is obstructed.

2. A door of the class described having two parts arranged for swinging movement between open and closed positions to control a doorway, one of said parts being arranged to provide, in closed position, a clearance between its free edge and the corresponding side of said doorway, of insufficient amount to permit passage of a person therethrough, power means associated with said part for moving it to its closed position, the other door part being arranged for cooperation with said first part to complete the closure of said doorway when in closed position, and means interconnecting said door parts to cause their normal operation together as a unit, and including means breakable to permit said power means to close said first part when said second part is obstructed.

3. A door of the class described having two parts arranged for movement between open and closed positions to control a doorway, one of said parts being of grille type and arranged to provide, in closed position, a clearance from a side of said doorway of insufficient amount to permit passage of a person therethrough, power means associated with said part for moving it to its closed position, the other door part being solid and arranged for cooperation with said grille part to complete the closure of said doorway when in closed position, and means interconnecting said door parts to cause their normal operation together as a unit and including means breakable to permit closure of said grille part by said power means upon obstruction to said solid part.

4. A door of the class described having two parts arranged for swinging movement between open and closed positions to control a doorway, one of said parts being arranged to provide, in closed position, a clearance between its swinging edge and the near side of said doorway, of insufficient amount to permit passage of a person therethrough, power means associated with said part for closing it, the other door part being arranged for cooperation with said first part to complete the closure of said doorway when in closed position, and means interconnecting said door parts to cause their normal operation together as a unit and including means breakable to permit said power means to close said first part when said second part is obstructed and means providing swinging motion between said door parts under such emergency condition.

5. A door of the class described having two parts arranged for swinging movement between open and closed positions to control a doorway, one of said parts being arranged to provide, in closed position, a clearance between its free edge and the corresponding side of said doorway, of insufficient amount to permit passage of a person therethrough, power means associated with said part for moving it to its closed position, the other door part being arranged for cooperation with said first part to complete the closure of said doorway when in closed position, and means interconnecting said door parts to cause their normal operation together as a unit, and including means hingedly mounting said second door part upon said first door part, and means securing said second door part against movement upon its hinge and breakable to permit said power means to close said first door part when said second part is obstructed.

6. A door of the class described having two parts arranged for swinging movement between

open and closed positions to control a doorway, one of said parts being arranged to provide, in closed position, a clearance between its free edge and the corresponding side of said doorway, of 5 insufficient amount to permit passage of a person therethrough, power means associated with said part for moving it to its closed position, the other door part being arranged for cooperation with said first part to complete the closure of said 10 doorway when in closed position, and means interconnecting said door parts to cause their normal operation together as a unit, and including means mounting said second door part upon said first door part for movement relative thereto about an 15 axis adjacent that of said first door part and means breakable to permit said power means to close said first door part upon obstruction to said second door part.

7. A door of the class described having two parts arranged for swinging movement between open and closed positions to control a doorway, one of said parts being of vertically barred type and arranged to provide, in closed position, a 5 clearance from a side of said doorway of insufficient amount to permit passage of a person therethrough, the other door part being solid and arranged for cooperation with said barred part to complete the closure of said doorway when in 10 closed position, said solid door part being hingedly mounted upon said barred door part adjacent the hinge of the latter, and means connecting said solid door part with a bar of said barred part and breakable to permit said power means to close said 15 barred part upon obstruction to said solid part.
